(57) **CLAIM**

The ornamental design for an integrated console product, as shown and described.

DESCRIPTION

FIG. 1 is a top right front perspective view of an integrated console product in an environment showing my new design; FIG. 2 is a front right bottom perspective view thereof; FIG. 3 is a front elevational view thereof; FIG. 4 is a left side elevational view thereof, which is a mirror image of right side elevational view thereof; FIG. 5 is a top plan view; and, FIG. 6 is a bottom plan view.

The broken line showing of environment is for illustrative purposes only and forms no part of the claimed design.
